PORTABLE ELECTRIC TOOL AND CASING

Alonzo Galloway Decker, Towson, Md., assignor
to The Black & Decker Manufacturing Com-
pany, a corporation of Maryland

Application March 23, 1937, Serial No. 132,658

10 Claims. (Cl. 77—6)

The invention relates to a portable power-driven tool of the rotary type.

While a drill has been chosen as the particular embodiment of the invention to be described, the invention is adapted to more general application, being capable of use in portable power-driven rotary tools for various purposes, as tapping, sanding, grinding, and polishing; and while certain features of the invention relate particularly to electric tools, other features are capable of more general application.

The object of the invention is to produce a tool of this type which, though capable of general use, is more particularly adapted for use in confined or restricted spaces where a tool of the usual dimension in the direction of the axis of the bit cannot be introduced, the tool of the invention having greatly increased facility for use in this way as compared to existing types.

20 The improved tool to which the invention is applied has the axis of the spindle, the chuck, and the bit transversely related to the motor axis and, in accordance with the invention, the tool is so arranged and proportioned that it can be held in and directed by one hand, which is an important advantage, as there are many instances in which it is difficult or impossible for the operator to reach with both hands the locality where the work is to be done, and it also frequently occurs that one hand of the operator may be otherwise engaged, as in holding other tools, positioning the work, or maintaining the working position.

25 The tool of the invention has the further important advantage that it is so arranged that the fingers of the hand of the operator, which is guiding and directing the tool, may engage the tool casing immediately adjacent the shank of the bit, thus effecting a most satisfactory guidance of the tool when supported in one hand, the tool case—or, more particularly, the gear casing at the head—being so arranged that the fingers of the operator in this position are protected from contact with the rotating chuck.

30 In order to arrange to the best advantage for the one-hand operation described, the gear casing is provided with a nose surrounding the chuck and is further so formed and arranged that the hand may grip the gear casing with the palm of the hand engaging the casing directly back of and in line with the bit and the axis of the chuck, the gear casing being arranged and of such configuration and so proportioned as to its length that the fingers grip the nose and are free from contact with the rotary chuck.

35 While the relation of the palm grip to the nose whereby the fingers engage the nose near the drill shank is of great importance and advantage, the palm grip is of advantage independently of the chambered nose.

40 It is a further important accomplishment of the invention that air is supplied without interruption to the motor for cooling and also to the gear casing for cooling the latter, the ventilation being so arranged that it is not impeded or interfered with by the hand of the operator in the position described, it being an important advantage in this type of tool that the air draft passes either through or along the outer surface of the gear case, thus helping to cool the gear case and avoiding over-heating of the gear case which would be highly detrimental to the one-hand operation described.

45 While the drill or other rotary tool of the invention is particularly adapted to be directed and supported by one hand of the operator in the manner already suggested, it can also be supported and directed by the operator using one or both hands to grasp the motor case or field case, the axis of which is transverse to the bit and tool spindle. By thus handling the tool it can, for some purposes, be introduced into even smaller spaces than when supported and directed in and by one hand grasping the gear case. Where the tool is directed by grasping the motor 50 housing or barrel, two hands are generally necessary to exert sufficient pressure in the direction of the bit axis to secure proper operation of the tool.

55 It is also of advantage that the gear case and motor case are preferably threaded together, the casing being combined without the use of screws, bolts, and the like. It is of further advantage, contributing to the adaptability of the tool for use in places generally considered inaccessible for work with power tools, that the tool is of a dimension in the direction of the axis of the drill bit which is approximately half the length of the previous tools, being approximately three inches whereas the shortest full-powered drill on the market is about seven inches long. The drill of the invention is fully powered, being preferably driven by a small high-speed motor.

In the drawings:

Figure 1 is a full size side elevation of the tool 50 in the form which is now regarded as the preferred form of the invention.

Figure 2 is an elevation looking at the tool from the left in Figure 1.

Figure 3 is a fragmentary view on an enlarged 55

scale, the same being broken away to show the interval construction of the tool on a plane of the axis of the motor.

Figure 4 is a section in the plane of the motor 5 and spindle axis.

Figure 5 is a section in the line 5—5 in Figure 4.

Figure 6 is an elevation corresponding to Figure 1 and showing a second form of tool.

Figure 7 is a section on line 7—7 in Figure 6. 10 Figure 8 is an elevation illustrating a third form of the tool.

Figure 9 is a sectional elevation looking to the left in Figure 8.

Figure 10 is an elevation of the tool of the type 15 shown in Figure 1, showing the manner of grasping the same by the hand in the single-handed control of the tool, half size.

Figure 11 illustrates the operation of the tool in a confined place, as between the struts of an 20 airplane wing, the drilling and assembling of which is an operation to which the tool is particularly adapted.

Referring to the drawings by numerals, each 25 of which is used to indicate the same or similar parts in the different figures, the construction shown having particular reference to Figures 1, 2, 3, 4 and 5, comprises an electric motor 1 enclosed in a field case or motor housing 2. This field case or motor housing 2 is closed at one end 30 by a brush and switch housing 3 and at the other end by a gear casing 4. These are rigidly secured in any suitable manner, preferably as hereinafter described. The field case 2, of which the brush housing is an extension, is referred to as the 35 barrel.

In the preferred form of the invention shown, the motor shaft 5, which is preferably in the line of the axis of the casing, has secured thereto and mounted thereon at one end of the motor a 40 ventilating or cooling fan 6. In the form shown the fan draws air through and around the motor in accordance with the usual practice in motor ventilation, the air being introduced through ventilating holes 7 in the field casing 2, passed 45 to the left around the motor and between the armature and field and ejected through and by way of the draft passages 9, 8 in the gear casing and the ring 12. It is of interest in the construction of the casing that the field or motor casing 50 2 has a threaded connection at 11 with a ring 12 which has a central bearing boss 10 which is threaded into the gear casing 4 at 14, the nose 15 which encloses the chuck 16 in a manner to be described being threaded into the gear casing 55 4 at 17.

The gear casing 4 is provided with bearings 18 and 19 in which a tool spindle 20 is supported at right angles to the motor axis, being driven by pinion 21 on the motor shaft 5, which pinion 60 meshes with the toothed gear 22 mounted on and secured to the spindle. The motor shaft is supported in bearings 24 in the ring 12 immediately adjacent the pinion 21 and between the fan 6 and said pinion. It is also of interest that the 65 bearing portion of the ring is connected to the ring proper by radial ribs 12' between which are passages or openings 8' which connect the fan chamber 31 to the annular passage 8, all details being subject to variation.

It is an important feature of the invention that 70 the gear casing 4 supporting the spindle 20 at right angles to the motor shaft is constructed of a size and shape to fit within the palm of the hand. In the most highly developed form it is so proportioned and arranged that the fingers ex-

tend down over the sides of the gear casing 4, with their ends bearing on the nose 15 of the casing, as best illustrated in Figure 10. This arrangement is best adapted to the direction of the tool when held in one hand. 5

As seen from the left in Figure 1, and as seen in Figure 2 the gear casing 4 and nose 15 together form a pear shaped body, the pear being inverted in both views and having its small end downwardly disposed. The spindle has its axis 10 at right angles to the barrel axis which is also the motor axis and the long axis of the pear shaped body coincides with the spindle axis. The chuck 16 is in the small end of the pear, and the large end of the pear is of spherical contour 15 about the upper end of the spindle presenting a ball like grip for the hand at the upper end of the spindle and closing the end of the barrel which is of substantially the same radius as the large end of the pear. 20

The head or gear casing 4 may be described in connection with nose 15 as in the form of an elbow continuous with the front end of the barrel which is treated as horizontal the elbow having a downwardly reducing taper. The convex portion of the turn of the elbow is also regarded as of ball like formation affording a satisfactory palm grip the fingers extending downwardly over the nose which constitutes the reduced end of the taper. 25

The term zone as used herein has reference to a band shaped area of the nose surface extending around the same at right angles to the nose axis.

In order to illustrate the size and proportions of the casing, this casing with other parts is 30 drawn full size, particularly in Figures 1 and 2, the gear casing as shown being slightly over three inches from its back surface at 25 in line with the drill axis to the end of the nose at 26, and approximately two and one quarter inches in 40 width from 27 to 28 in Figure 2, it being understood that these dimensions are subject to variation though the dimensions shown are regarded as most convenient for the average operator, particularly for the one-handed support and control 45 of the tool.

In accordance with the preferred arrangement, the chuck 16 is mounted directly on the lower end of the tool spindle 20 and secured in any suitable manner. It is of particular advantage that the nose 15 be chambered as at 29 to receive and enclose the chuck 16, the lower edge of which may protrude at 16' as illustrated in Figure 1, the nose 15 and the gear casing 4 being preferably so proportioned that the protruding portion 16' of 55 the chuck is below the grasp of the fingers, though other features of the invention may be utilized with a different arrangement of the chuck, and this type of nose has separate utility.

While the tool of the invention is particularly 60 adapted to be grasped and directed by and with one hand of the operator, it is also to be noted that it may be supported and directed by both hands grasping the barrel or the motor casing 2 and that, when thus held, work can be performed 65 under some circumstances in even more confined spaces than when the tool is supported and directed by one hand grasping the gear casing as shown in Figures 10 and 11. The ability to support and direct the tool by and with one hand, 70 however, has important advantages as already suggested. Some of the features described are independent of the type of motor. The usual practice provides that the electric motor be ventilated by means of a fan which passes air around 75

the motor, the air being introduced through a series of holes at one end of the casing and exhausted through a corresponding series of holes at the other end of the casing, one set of holes being at the end of the field casing in the vicinity of the gear casing. An important difficulty encountered in the development of the present tool has been due to the fact that in grasping the tool about the gear casing as shown in Figure 6 the latter mentioned set of ventilating holes is completely or almost covered so that the ventilating air is cut off from the motor and heating results. To overcome this difficulty the applicant has provided the ventilating system illustrated in the preferred form in Figures 1 to 5 and in a modified form in Figures 6, 7, 8, and 9. In accordance with this system, the air may be forced or projected by the fan 6 through annularly arranged openings 8 and 8' which lead from the fan chamber 31 to the annular discharge 32 at the left or forward edge of the ring 12, which ring is an extension of the field casing 2, which is provided for convenience of construction in this form of the tool, and is omitted or made integral with the field casing in other forms shown.

The draft openings 8 and 32 extend substantially around the casing circumferentially of the motor shaft providing a passage around the entire periphery of the casing including a slot at the bottom adjacent to nose 15. To prevent cutting off of the air draft in case the hand, in holding the tool, covers a large portion of the peripheral draft opening 32 or any similar draft opening, the surface of the gear casing 4 is grooved or corrugated, the corrugations or grooves 9, in the preferred form shown, extending from the peripheral draft opening 32 in any suitable arrangement along the surface of the casing and being to best advantage turned from a direction in substantial parallelism with the motor axis at 35 downwardly at 30 so that they approach the direction of the bit axis and the axis of the tool spindle which is at right angles to the motor axis. The exact angle of the bit axis and spindle axis is subject to variation if desired, the right angled relation being preferred for convenience in driving. The arrangement of the grooves 9 as shown provides a free discharge for the ventilating air under all circumstances of holding, as suggested in Figure 10, and also provides for the cooling of the gear casing, which is an important advantage, particularly in operating the tool when directed and supported by and in one hand with the gear casing gripped as described or in some similar manner. The slot 33 would not be covered at any time.

While the fan 6 has been described as discharging air toward the gear casing, the vacuum thus created serving to draw through the motor air which is introduced at the openings 7, a change of the angle of the fan blades which would cause the air to be drawn in through the gear casing 4, passed through the motor and discharged by way of the openings 7, is a non-inventive variation which is contemplated, the direction of the draft being a matter of selection.

Figure 6 shows a modified form of the tool in which the air draft propelled by the fan 40 on the shaft 41 of the motor 42 is released or admitted by way of a series of holes 43 suitably arranged about the gear casing 44, and, further, by way of a slot 45 of any convenient shape at the bottom of the casing, preferably discharging adjacent the nose 46 preferably enclosing the chuck 47 in the manner previously described, it

being further understood that the holes 43 may be of any suitable shape and in any suitable arrangement about the gear casing, the purpose being to avoid closing these holes or the majority of them when the gear casing is gripped by the hand after the manner illustrated in Figure 10 or in any manner suitable to the supporting and directing of the tool by one hand of the operator. In this connection, slot 45 being of large dimensions in comparison to the holes 43 serves to release a large portion of the air necessary to cool the motor, giving effective cooling when the holes 43 are partially covered, the draft through holes 43 being, however, sufficient to cool the gear casing 44. The holes 43, as shown, are preferably inclined outwardly and forwardly away from the fan, being connected to the fan chamber 40 by a series of corresponding holes 48 drilled in the rear wall 49 of the gear casing, being parallel to the motor axis or at any suitable angle, it being understood that the arrangement shown is chosen largely for convenience in the formation of the holes by drilling, which contributes to low cost production. It may be further noted that the air is fed to or from the slot 45 by a plurality of the holes 48 as shown in Figure 7. In this connection, it is to be understood that the draft passages 43, 48, and 45 are subject to considerable variation and that the blades 50 of the fan 40 may be inclined at any suitable angle to pass the air either in the direction shown; i. e., drawing it into the casing by way of the openings 51, passing it over the motor to the left, and discharging it by way of the holes 43 and the slot 45, or in the opposite direction, so that it is drawn in at 35 43, 45 and passed to the right through and about the motor and discharged at 51. While the cooling of the gear casing and motor in this or some equivalent manner is of great advantage, the other features of the invention may be utilized 40 without this provision.

The gear connections not shown may be arranged in any suitable manner, the connections shown in Figure 4 being suitable to the various types of tool illustrated.

In the form of casing shown in Figure 6, the ring 12 of the previous construction has been omitted, the casing consisting in this instance of the field or motor casing 53, constituting the main feature of the barrel, the brush and switch 50 housing 54, and gear casing 44. The latter, in the most highly developed form, has a nose 46, chambered to receive the chuck 47. The nose 46, as previously described, provides an engagement for the fingers immediately adjacent the bit 55 shank for directing the drill or other bit 13, as shown in Figure 10. While this arrangement of nose and chuck is of great advantage, the other features of the invention may be otherwise associated.

The casing members 44 and 53, have a threaded engagement at 55 as already suggested in connection with the construction previously described, obviating use of screws or bolts in connecting these elements of the casing, this and other details being subject to wide variation.

Figures 8 and 9 show still another form of the tool in which the motor 60 is ventilated by passages 61 leading directly from the rear face 62 of the gear casing 64 through the same to its 70 forward curved surface at 65, the said passages 61 being preferably of elongated cross section. The elongated sides 66 of these openings are preferably curved concentrically with the motor axis as shown in Figure 9, or this may be referred to 75

as a convenient shape giving an increased cooling area in the casing 64 and increased air draft capacity, the exact shape of the cross section of the openings being subject to variation. It is 5 also to be noted that in this construction the bottom opening or passage 61 terminates in a downwardly disposed slotted opening 66 which affords a free discharge for a considerable volume of ventilating air at the bottom of the barrel 67 10 of the casing, where it is substantially out of reach of the fingers of the operator in holding the tool in the manner shown in Figure 10, so that it is not subject to closing by covering in this way. Further, there is practically no possibility that 15 the holes or outlets 68 from the passages 61 will be covered by the hand in so large a proportion at any one time as to interfere with the cooling of gear casing 64. The construction shown in Figure 8 gives a satisfactory result in the cooling 20 of the motor and in the cooling of the gear casing so that it can be gripped in the manner described without discomfort or loss of efficiency on the part of the operator.

The improved portable electric tool construction shown represents an important advance in the production of a portable electric tool of the rotary type for use as a drill, screw-driver, wrench, or for other purposes, and is particularly adapted for use in confined and restricted spaces 30 where a tool of standard dimensions cannot be introduced and also where operation and direction of the tool by one hand of the operator is of advantage, the point of application of the tool being either inaccessible to both hands of the 35 operator or the other hand being, in many instances, necessary to support the operator in working position, or to hold the work, or the like.

It is further noted that, while the tool is particularly adapted to be held and directed in one 40 hand, it may be directed and operated in still more restricted locations, giving the full benefit of the short dimension of the tool in the direction of the bit axis, by grasping the tool casing with both hands, particularly the barrel thereof, 45 back of the gear casing or head.

It is also an important advantage contributing to the operation of the tool; i. e., the supporting and direction of the same by one hand, that the 50 rotary chuck is enclosed within the nose of the drill casing which is chambered for this purpose, giving support for the finger ends or a point of engagement therefor on the tool casing immediately adjacent the shank of the bit. This contributes to more perfect and accurate direction of the tool by one hand, and protects the 55 fingers from the chuck.

The cooling feature is also of importance in this connection and otherwise in that it provides efficient cooling of both the motor and the gear 60 casing even though the latter is largely covered by the hand which grasps the tool by the gear casing in the manner described. This feature whereby the gear casing is cooled is almost essential in connection with an electric tool which 65 is to be supported and directed by one hand holding the gear casing in the manner described, with the back of the same in the palm of the hand, whereby heating would interfere seriously with the efficiency of control by the operator.

70 While the various features described may be used independently, they cooperate in the construction shown and contribute to the common result in the production of a one-hand control type of tool which is of widely increased efficiency for the purposes described.

It is to be further noted that the tool described is of particular advantage among other uses to which it may be applied in assembling the frames of airplane wings and the like, as shown at 75 in Figure 11, where it is necessary to operate a drill or nut runner between the struts 76 and inside the wings, and hence in localities which are closely restricted as to the dimensions of any tool which can thus be employed. In many instances it can be employed where hand operations were 10 formerly necessary, being adapted to all classes of rotary tool work.

I have thus described a portable rotary electric tool embodying the features of my invention in the preferred and in certain modified forms, the 15 description being specific and in detail in order that the manner of constructing, applying, operating, and using the tool may be understood; however, the specific terms herein are used descriptively rather than in a limiting sense, the 20 scope of the invention being defined in the claims.

What I claim as new and desire to secure by Letters Patent is:

1. A portable, power-driven rotary tool for use 25 in assembling and similar work particularly in confined spaces comprising a barrel and a head at one end of the barrel, said head having spindle bearings and a spindle therein substantially at right angles to the barrel axis, and a nose at one 30 end of said spindle encircling the spindle and integral with the head, the head being of a size and proportion and being adapted to be enclosed within the palm of the hand with the finger ends 35 engaging the nose to support and direct the tool, the nose being chambered to receive and contain a chuck on the end of the spindle, the barrel being adapted to contain a motor driving said spindle through angular connections in said head, and the head being rigidly connected to the 40 casing.

2. A portable power-driven rotary tool for use 45 in assembling and similar work particularly in confined spaces comprising a barrel to serve as a motor casing and a head closing one end of the 50 barrel and rigidly secured thereto, the head having a spindle therein and a nose integral with the head and surrounding the lower end of the spindle and chambered to receive a chuck on said spindle, the axis of the nose and the spindle and 55 chamber being substantially at right angles to the barrel axis, the head being convexly rounded about the upper end of said spindle and proportioned to fit in the palm of the hand with the finger ends engaging the lateral surface of the nose which is of less diameter than the rounded upper portion of the head, whereby the tool is 60 adapted to be directed and supported by and with one hand of the operator, the fingers being protected from contact with the chuck.

3. A portable rotary electric tool for use in 65 assembling and similar work particularly in confined spaces having an electric motor, a field casing therefor, a gear casing rigidly secured to and substantially closing an axial end of the 70 field casing, a spindle in the gear casing substantially at right angles to the motor axis, the gear casing having a smoothly curved convex external surface surrounding and overlying the upper end of the spindle and adapted to fit in the palm of the hand and to be gripped by one hand, whereby the tool is adapted to be directed and supported by one hand of the operator, a 75 chuck on the opposite end of said spindle, the gear casing having a finger grip surrounding the

spindle, and of less diameter than the said upper convex surface of the gear casing, and rigidly attached thereto, the said grip being adjacent the chuck and adapted to be engaged by the 5 fingers of the hand which encloses the gear casing.

4. A casing for a portable rotary electric tool for use in assembling and similar work particularly in confined spaces comprising a barrel 10 adapted to enclose a motor having its axis parallel to the barrel axis and a head closing the front end of the barrel and provided with bearings to support a spindle transverse to the motor axis, the head being in the form of an elbow having 15 a ball like rounded external surface surrounding the upper end of the spindle, the same being shaped and proportioned to serve as a one-hand grip, whereby the tool is adapted to be supported and directed by one hand of the operator, 20 the barrel having air passages and the head being provided with air passages in its surface continuous with the air passages in the barrel for ventilating the casing and head, the air passages in the head comprising openings spaced away 25 from the area contacted by the hand in gripping the head.

5. A casing for a portable electric tool for use in assembling and similar work particularly in confined spaces comprising a barrel adapted to 30 support an electric motor with its axis extending substantially in the direction of the axis of the casing, a gear casing secured to the end of the barrel and adapted to support a spindle substantially at right angles to the motor axis, the gear 35 casing being of inverted pear shape and proportioned to be enclosed in the palm of the hand of the operator and having a ball like palm-engaging portion enclosing the upper end of the spindle and a rigidly supported finger-grip portion 40 near the lower end of the spindle, and adapted to be engaged by the fingers of the hand which encloses the gear casing, the gear casing having ventilating passages and the barrel having ventilating passages and means adapted to 45 cooperate therewith to ventilate the gear casing and the motor casing, the ventilating passages in the gear casing comprising grooves in the surface of said casing traversing a substantial portion of the surface of said casing and connected to the 50 passages in the barrel.

6. A casing for a portable electric tool for use in assembling and similar work particularly in confined spaces comprising a field casing adapted to support an electric motor with its axis extending substantially in the direction of the axis of the casing, a gear casing secured to the end of the field casing and adapted to support a spindle substantially at right angles to the motor axis, the gear casing being shaped and proportioned 55 to be enclosed in the palm of the hand of the operator and having the palm-engaging portion covering one end of the spindle and a finger-grip portion adjacent the other end of said spindle, and adapted to be engaged by the fingers of the 60 hand which engages the palm portion, the gear casing having ventilating passages and the field casing having ventilating passages and other means adapted to cooperate therewith to ventilate the gear casing and the field casing, the ventilating 65 passages in the gear casing comprising grooves in the surface of said casing disposed in the direction of the axis of the field casing.

7. A casing for a portable electric tool for use in assembling and similar work particularly in confined spaces comprising a field casing adapted to

support an electric motor with its axis extending substantially in the direction of the axis of the casing, a gear casing secured to the end of the field casing and adapted to support a spindle substantially at right angles to the motor axis, the gear casing being pear shaped with the axis of the pear coinciding with the axis of the spindle, said gear casing being proportioned to be enclosed in the palm of the hand of the operator and having the palm-engaging portion which is the large end of said pear shaped casing smoothly rounded for this purpose, and substantially enclosing the upper end of the spindle and a finger-grip portion at the lower end of said spindle, said finger grip being rigidly supported on the gear casing, and adapted to be engaged by the fingers of the hand which encloses the gear casing, the gear casing having ventilating passages and the field casing having ventilating passages and other ventilating means adapted to cooperate therewith to ventilate the gear casing and the field casing, the ventilating passages in the gear casing comprising grooves in the surface of said casing, inclined to the direction of the axis of the gear casing and connected to the passages in the field casing.

8. A portable power driven rotary tool particularly adapted for use in assembling work, and for operation in confined spaces, the same having a casing, comprising a barrel in the nature of a field casing for an electric motor, and a head closing one end of the casing, the head being rigidly secured and having spindle bearings and a spindle therein at right angles to the barrel axis, the head being in the form of an elbow, one arm of which is continuous with the barrel, the elbow having a ball like convex bend, the ball like portion overlying and with the adjacent end portion of the barrel surrounding the upper end of the spindle, the other arm of the elbow having a reducing taper downwardly from said ball like portion, the tapered portion being in the nature of a nose surrounding the lower end of the spindle and being rigidly secured to the head and chambered to contain a chuck on the end of said spindle, the ball like portion being adapted to fit in the palm of the hand, the fingers engaging the nose whereby the tool is held and directed in and by one hand.

9. A portable power driven rotary tool for use in assembling and similar work and particularly adapted for operation in confined spaces, the same comprising a barrel having a motor therein and a head rigidly secured to the barrel at one end, said head having spindle bearings and a spindle therein transverse to the barrel axis and a nose at the lower end of said spindle encircling the spindle and rigidly supported relatively to the barrel, the head being of rounded ball-like shape about the upper end of the spindle and of a size and proportions adapted to be enclosed within the palm of the hand with the finger ends extending over and engaging the nose to support and direct the bit, the nose being chambered to receive and enclose a chuck on the lower end of said spindle whereby the fingers are protected from contact with the chuck as it rotates and the motor having a driving connection with said spindle.

10. A portable power driven rotary tool for use in assembling and similar work and particularly adapted for operation in confined spaces, the same comprising a barrel having a motor therein and a shaft driven by the motor, a head rigidly supported on the barrel, said head having spindle bearings and a spindle therein transverse to said

shaft, which has a driving connection to said spindle, a nose at the lower end of said spindle encircling the spindle and rigidly supported, the head being of rounded ball-like shape about the upper end of the spindle and of size and proportions adapted to be enclosed within the palm of the hand with the fingers extending over and

engaging the nose to support and direct the bit, the nose being chambered to receive and enclose a chuck on the end of said spindle whereby the fingers are protectd from contact with the chuck as it rotates.

ALONZO GALLOWAY DECKER.
